FOUNTAIN PEN

Glenn E. Johndohl and Clifford M. Sublette,
Denver, Colo.

Application September 8, 1936, Serial No. 99,715

8 Claims. (Cl. 120—42)

This invention relates to a fountain pen and to means for furnishing ink to a fountain pen. The principal object of the invention is to provide a simple, and highly efficient ink cartridge and a pen for receiving said cartridge so that the user may purchase his ink in a cartridge which can be slipped into the pen and which will be automatically opened by the pen so as to be ready for use, thus making it unnecessary for the user to ever contact the ink in its liquid state.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a perspective view of the improved pen.

Fig. 2 is a side view of the cartridge employed in the pen.

Fig. 3 is an end view of the cartridge.

Fig. 4 is an end view of the sleeve.

Fig. 5 is a side view of the cartridge sleeve.

Fig. 6 is a longitudinal section through the cartridge with the sleeve in place thereon.

Fig. 7 is a longitudinal section through the pen, illustrating the operation of opening the cartridge.

The pen consists of a tip portion 10 for supporting the usual pen point 11. The tip portion and the ink feeding mechanism therein may have any of the usual constructions. The upper extremity of the tip portion is threaded to receive a barrel 12 and the upper extremity of the barrel 12 is internally threaded to receive a cap 13. These parts comprise the complete pen.

The ink is furnished for the pen in a cartridge 14, as shown in Figs. 5 and 6. The cartridge is of sufficient length to extend within the cap 13 and is formed with a tapered neck portion 17 for receiving a sleeve 18. The neck portion 17 is

of smaller diameter than the remainder of the cartridge and joins the latter to form a shoulder thereon.

The sleeve 18 is formed with a central air tube 19 supported therein upon a cross bar 20 or in any other suitable manner. The cartridges are furnished to the user with the sleeve 18 in place on the neck 17, as shown in Fig. 6, and with a cork 21 at the shoulder between the neck and the cartridge for holding the ink in place therein.

To install the cartridge in the pen, the user re-

moves the cap 13 from the barrel 12 and drops the cartridge in place in the latter. This allows the head of the sleeve 18 to engage a gasket 22 which seals it against the tip portion 10. The cap 13 is now put in position and threaded into the barrel 12. The inward movement of the cap forces the cartridge into the barrel and into the sleeve 18, wedging the latter into the neck 17.

As the sleeve 18 moves onto the neck 17, the air tube 19 contacts the stopper 21 and pushes the latter from its seat in the neck 17. This allows the ink to flow directly through the neck and into the tip portion 10, and also allows air to flow backwardly through the air tube 19 into the cartridge 14. If the stopper is formed of cork or other light material, it will immediately float to the upper extremity of the pen as shown in Fig. 1 so as not to interfere with the flow of ink from the cartridge.

After the ink has been used, the cap 13 is removed and the cartridge with its sleeve 18 is discarded and replaced. It is desired to call attention to the fact that all operating parts, such as the small air tube 19, etc. are discarded and renewed with each filling of ink so that the pen is maintained in the highest state of efficiency at all times.

It is desired to call attention to the fact that the flow of ink in this improved pen is always toward the pen point. The direction of flow is never reversed as it is in filling the usual pen. Therefore no foreign substances can be drawn into the pen to clog the flow passages thereof. There are no working parts such as ink sacks, plungers, etc. to become worn and damaged. The ink never contacts the barrel of the pen so if desired this may be made transparent and will remain so indefinitely.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A cartridge for filling fountain pens comprising: tubular ink retaining portion; a neck portion; a stopper closing said neck portion; a sleeve fitted over said neck portion; a projecting member carried by said sleeve and extending within said neck portion a distance sufficient to force said stopper from place when said sleeve is forced in position on said neck portion.

2. A cartridge for filling fountain pens comprising: tubular ink retaining portion; a neck portion; a stopper closing said neck portion; a sleeve telescopically fitted over said neck portion; a cross member in the head of said sleeve; and a projecting member extending from said cross member into said neck portion into contact with said stopper, said projecting portion having a length sufficient to force said stopper from place when said sleeve reaches its final position. 5
3. A cartridge for filling fountain pens comprising: a tubular ink retaining portion; a neck portion; a stopper closing said neck portion; and a pushing member mounted in said neck for pushing said stopper from position after said cartridge is in place in a pen, said pushing member being hollow so as to form an air tube and being of less diameter than said neck to allow the ink to flow through said neck around said pushing member. 10
4. A fountain pen comprising: a tip portion; a barrel portion; a cap portion; a cartridge carried in said barrel; a stopper closing the forward extremity of said cartridge; and a projecting member abutting said tip portion to force said stopper from place as said cartridge is forced into said barrel. 15
5. A fountain pen comprising: a tip portion; a barrel portion; a cap portion; a cartridge carried in said barrel; a stopper closing the forward extremity of said cartridge; and a projecting member abutting said tip portion to force said stopper from place as said cartridge is forced into said barrel, said projecting member being hollow to admit air to said cartridge and being of less diameter than the passage in the forward extremity of said cartridge to allow the ink to flow from said cartridge about said projecting member. 20
6. In a fountain pen having a barrel and a pen-holding tip, provided with a central ink passage, threaded to the open extremity of said barrel; a tubular ink cartridge slideable into said barrel; a reduced neck portion on said cartridge; a stopper initially positioned in said neck portion; a cap member fitted over the extremity of said neck portion, said cap member being open at both extremities; a hollow air tube projecting from said cap member into said neck portion and means on said cap member for supporting said air tube axially within said cap, said air tube projecting from said cap sufficiently far to force said stopper from said neck portion and into said cartridge as said cap member moves into position on said reduced neck portion. 25
7. In a fountain pen having a barrel and a pen-holding tip, provided with a central ink passage, threaded to the open extremity of said barrel; a tubular ink cartridge slideable into said barrel; a reduced neck portion on said cartridge; a stopper initially positioned in said neck portion; a cap member fitted over the extremity of said neck portion, said cap member being open at both extremities; a hollow air tube projecting from said cap member into said neck portion; and means on said cap member for supporting said air tube axially within said cap, said air tube projecting from said cap sufficiently far to force said stopper member from said neck portion and into said cartridge as said cap member moves into position on said reduced neck portion, the length of the cartridge with relation to the length of said barrel being such that the pen-holding tip of said pen will force said cap onto said neck portion as said tip is brought to position on said barrel. 30
8. An ink cartridge for fountain pens of the cartridge filling type comprising: a relatively long tubular container closed at one extremity; a reduced neck portion on the other extremity of said container joining the latter to form a shoulder thereon and being slightly tapered toward its open extremity; a tapered, tubular cap member forced onto the tapered extremity of said neck portion; a cross member in the head of said cap member; an air tube supported by said cross member and extending axially through said cap member and projecting from the other extremity thereof into said neck portion; and a stopper in said neck portion adjacent said shoulder, said air tube terminating adjacent said stopper so that when said cap member is forced onto said neck portion up to said shoulder, said air tube will force said stopper from said neck portion and into said cartridge to allow the ink to flow from said cartridge about said air tube while the air enters through said tube. 35
